The ornamental design for the portable electric hammer drill, as shown and described.

DESCRIPTION

FIG. 1 is a front perspective view of the portable electric hammer drill;

FIG. 2 is a front elevation view thereof;

FIG. 3 is a rear elevation view thereof;

FIG. 4 a left side elevation view thereof;

FIG. 5 is a right side elevation view thereof;

FIG. 6 is a top plan view thereof; and,

FIG. 7 is a bottom plan view thereof.
